LOOSE LEAF BINDER

Reginald M. Raynolds, New York, N. Y.

Application October 10, 1934, Serial No. 747,700

8 Claims. (Cl. 129—8)

My present invention relates generally to loose-leaf binders, and has particular reference to an improved and simplified post binder.

The present invention is designed primarily for the purpose of providing a binder which will removably accommodate a relatively large mass of looseleaf sheets; and it is a general object of my invention to provide a structure which is composed of a minimum of parts, simple and inexpensive to manufacture, easy to use, and of an enhanced rigidity and firmness.

A more particular object of the invention is to provide a binder which can be readily adjusted between a normal closed position, a partially extended position in which the pages are more readily accessible for reading or reference, and a completely extended and adjusted loading position.

A binder of the general type to which my invention relates consists essentially of a front and rear cover, a medial back, and a plurality of posts adapted to extend through suitable marginal perforations in the sheets that are to be accommodated in the binder. The present construction is characterized by the provision of a pair of opposed U-shaped strips, a means for articulating each arm of one U to the corresponding arm of the other, and a pair of slidably superposed back elements in permanent interengagement. The base of each U carries a set of binder posts, and a hinge connection pivotally associates the base of one U with the outer edge of one of the back elements, and the base of the other U with the outer edge of the other back element.

One of the particular features of the present invention lies in providing a means for permanently interengaging one of the back elements with the other, whereby the back elements are constrained to a guided, relative sliding movement in substantially a single plane at all times.

Another feature of my invention lies in the provision of a novel type of latching arrangement for normally retaining the back elements in totally superposed or compacted relationship, for permitting said elements to be latched in a partially extended relationship, and for permitting a complete relative extension of the back elements.

The present construction is further characterized by the fact that the back elements resume their normal totally superposed and latched relationship when the binder is adjusted into loading position.

I achieve the foregoing objects, and such other objects as may hereinafter appear or be pointed

out, in the manner illustratively exemplified in the accompanying drawings, wherein—

Figure 1 is an exploded view of the U strips and the back elements entering into the present construction;

Figure 2 is a plan view of the binder, open, showing the parts in normal relationship;

Figure 3 is a view similar to Figure 2, showing the parts in partially extended relationship;

Figure 4 is a cross-sectional view taken substantially along the line 4—4 of Figure 2;

Figure 5 is an enlarged fragmentary cross-sectional view taken substantially along the line 5—5 of Figure 2;

Figure 6 is a view taken substantially along the line 6—6 of Figure 2, with a sheaf of looseleaf sheets in position;

Figure 7 is a view similar to Figure 6, showing the parts in partially extended position, corresponding to Figure 3;

Figure 8 is a view similar to Figure 7, showing a further extension of the parts preparatory to adjusting the structure into the relationship of

Figure 9, which shows the device in loading position.

One of the U-shaped strips entering into the present construction consists of the base 10 and the arms 11. The base carries a set of binder posts 12, the same being rigidly mounted on the base 10 and projecting in a direction parallel to the arms 11. Along one edge of the base 10, a series of spaced piano hinge bearings 13 is provided. In each of the arms 11 I provide a longitudinal slot 14, the same terminating at the outer end in a transverse portion 15.

The opposed U-shaped strip is substantially similar, having a base 16 and arms 17. The base is provided with the series of spaced piano hinge bearings 18, and carries the binder posts 19. These posts are not in alignment with the posts 12 but are adapted to position themselves in alternate relationship to the latter. In the illustrated embodiment, there are three posts 12 and two posts 19, and the looseleaf sheets which the binder is intended to accommodate are each provided with five suitably spaced perforations, one for each of the binder posts.

The length of the base 16 is slightly greater than that of the base 10, so that when the two U strips are assembled in opposed relationship the arms 17 will arrange themselves on the outside of the arms 11, as shown most clearly in Figures 2 and 3. Each of the arms 17 carries an inwardly projecting pin 20 which, during assembly of the device, is caused to extend through

the corresponding slot 14, so that each pair of articulated arms 11 and 17 is connected into a slideable and otherwise adjustable relationship, as will be more fully explained hereinafter.

5 For a purpose hereinafter to be specified, it may be desirable to provide each of the arms 17, on its outside surface, and near its end, with a knob 21.

10 The two back elements of the present structure are flat, substantially rectangular strips 22 and 23. The outer edge of the element 22 is provided with the spaced piano hinge bearings 24, constructed and arranged to align with the bearings 13, whereby a pivot pin may extend 15 through the aligned bearings and thereby establish a hinged connection between the U base 10 and the outer edge of the back element 22. The element 23 is similarly provided on its outer edge with the spaced piano hinge bearings 25 20 which are constructed and arranged to align with the bearings 18, whereby a pivot pin, extending through the aligned bearings, will establish a hinged connection between the U base 16 and the outer edge of the back element 23.

25 The lateral edges of the back element 23 are doubled back upon themselves, as shown at 26, for the purpose of slidably engaging around the corresponding lateral edges of the back element 22. Any other suitable or desired means may be provided for accomplishing this slideable and guided interengagement of the back elements.

30 For purposes presently to be described, the inner edge of the back element 22 is provided with the recess 27 and with the upstanding pin 28 near the inner end of the recess; and the back element 23 is provided near its outer edge with the upstanding pins 29 and 30.

When the parts are fully assembled and the back elements 22 and 23 are adjusted into their 40 totally superposed relationship, the posts 12 and 19 are all in parallel positions, as shown in Figure 2. A latch for keeping the parts in this relationship is provided and may be composed, for example, of the longitudinal strip 31 which is 45 mounted upon the pins 28 by means of the slots 32. A tension spring 33, connected at one end to the pin 38 on the back element 23, and connected at the other end with the pin 34 on the strip 31, tends to keep the strip 31 normally in 50 the position of Figure 2, in which the projection 35 is interposed in front of the pin 28. This prevents the back elements 22 and 23 from being slideably adjusted relative to each other. A medial opening 35' in the strip 31 accommodates the 55 spring 33 and the pin 30.

60 The outer exposed end of the strip 31 is bent into the form of a manually graspable tab 36 which permits the strip 31 to be adjusted longitudinally against the action of the spring 33. 65 When this is done, the pin 28 is released, and the back elements may be extended into the position of Figure 3, in which the pin 28 encounters the second projection 37 that is carried by the strip 31. By engaging the tab 36 and pulling the strip 31 against the action of the spring 33, the pin 28 can be again released, permitting the back elements to be slideably adjusted into their fully extended position, which is shown in Figure 8. In this position, the extension is limited by the engagement 70 of the pins 20 with the outer ends of the slots 14. In restoring the back elements to their normal positions, the inner edge of the back element 22 slides freely under the turned-up end 33 of the strip 31, and the pin 28 rides without obstruction 75 over the inclined cam surfaces 39. During

each encounter with one of the cam surfaces 39, the strip 31 is automatically moved against the action of the spring 33, ultimately springing back into its normal position and latching the pin 28, as in Figure 3 or in Figure 2.

5 The recess 27 is obviously for the purpose of permitting the pins 29 and 30 to be accommodated in the assembly.

10 The binder construction is completed, as will be understood, by the attachment in any suitable or desired manner of the front and rear covers 40 and 41. Preferably, each of these covers has a rigid end portion which is secured to the corresponding U base. For example, the portion 42 of the front cover may be glued or similarly attached to the outer surface of the base 10, and the portion 43 may be similarly attached to the outer surface of the base 16. Flexible connections 44 permit the covers of the binder to be spread, as shown in Figures 6 to 9, or to be 20 brought into parallel relationship like the covers of a book. It will also be understood that suitable covering material, either integral with or independent of the covers 40 and 41, may be provided to extend around the piano hinges and/or over the exposed outer surfaces of the back elements. Such additional covering material has been omitted from the present drawings because it forms no essential part of the present construction.

30 Assuming that the binder is empty and it is desired to load the same, the tab 36 is first manipulated with the finger to release the latch projections 35 and 37; and by pulling the covers 40 and 41 apart the parts may be separated into the 35 extended position of Figure 8. The knobs 21 are then grasped and pulled upwardly. This adjusts the articulated U arms into the angular relationship shown in Figure 9 and causes the back elements 22 and 23 to slide into normal superposed 40 relationship, as shown in Figure 9. During this relative closure of the back elements, the latch projection 35 automatically becomes operative to retain the back elements in this closed relationship. The pins 20 have in the meantime accommodated themselves within the slot portions 15, and a rigid and staunch triangular relationship is established, as shown most clearly in Figure 9, in which the binder posts 12 and 19 are in an opened and receptive position for the application thereto 50 of looseleaf sheets. The binder having been loaded, the tab 36 is again manipulated to release the latch projection 35, and by thereupon pulling the covers of the device apart the parts are restored into the extended position of Figure 8, in which 55 the binder posts are in parallel relationship. The parts are then pushed into mutual proximity to reestablish the normal bound relationship of Figures 2 and 6, and the binder automatically latches itself into this normal condition. It is then ready 60 to be used in the same way as an ordinary book would be used.

65 In the event that the binder is fully loaded it is sometimes desirable, in opening the same for reference or reading, to adjust the parts into the partially extended position of Figure 7. This is accomplished quite simply by merely releasing the latch projection 35 and pulling the binder covers apart until the pin 28 automatically comes into abutment with the latch projection 37. The 70 binder is thereafter restored to its normal position, as hereinbefore described, i. e., by merely pressing the parts toward each other.

75 It should be noted that during all manipulations the back elements are in permanent inter-

engagement and are constantly constrained to a sliding relationship in a substantially single plane. By virtue of this structural and functional feature, the manufacture of the device is extremely 5 simple and inexpensive, and the device as a whole proves easier to use and is of enhanced staunchness and rigidity at all times.

It will be understood that the opposed U strips and the slidable back elements of the present device 10 are preferably composed of metal, but that the features of the invention do not necessarily require metal to be employed where a similar rigid material is preferred.

In general, it will be understood that changes 15 in the details, herein described and illustrated for the purpose of explaining the nature of my invention, may be made by those skilled in the art without departing from the spirit and scope of the invention as expressed in the appended claims. It 20 is, therefore, intended that these details be interpreted as illustrative, and not in a limiting sense.

Having thus described my invention, and illustrated its use, what I claim as new and desire to 25 secure by Letters Patent is—

1. In a looseleaf binder, a pair of opposed U strips, a set of binder posts carried by the base of each U, a pair of slidably superposed back elements, means hinging the U bases to the outer 30 edges of the back elements, respectively, and means articulating each of the arms of one U to the corresponding arm of the other U to limit the pivotal movements of said U strips.

2. In a looseleaf binder, a pair of opposed U strips, a set of binder posts carried by the base of each U, a pair of slidably superposed back elements, means permanently interengaging said back elements to guide the relative sliding movements thereof, means hinging the U bases to the 40 outer edges of the back elements, respectively, and means articulating each of the arms of one U to the corresponding arm of the other U to limit the pivotal movements of said U strips.

3. In a looseleaf binder, a pair of opposed U strips, a set of binder posts carried by the base of each U, a pair of slidably superposed back elements, means permanently interengaging said back elements to guide the relative sliding movements thereof, releasable means for latching said 45 back elements in fully superposed relation, means hinging the U bases to the outer edges of the back elements, respectively, and means articulating each of the arms of one U to the corresponding arm of the other U to limit the pivotal movements of said U strips.

4. In a looseleaf binder, a pair of opposed U strips, a set of binder posts carried by the base

of each U, means permanently articulating each of the arms of one U to the corresponding arm of the other U and permitting the arms of each articulated pair to be superposed, extended into alignment, or angularly adjusted out of alignment, 5 a pair of slidably superposed back elements, and means hinging the U bases to the outer edges of the back elements, respectively.

5. In a looseleaf binder, a pair of opposed U strips, a set of binder posts carried by the base 10 of each U, each of the arms of one U being provided with a longitudinal slot, each of the arms of the other U being provided with a pin slidably engaging in the slot of the corresponding arm, a pair of slidably superposed back elements, means 15 permanently interengaging said back elements to guide the relative sliding movements thereof and constrain them to a common plane, and means hinging the U bases to the outer edges of the back elements, respectively. 20

6. In a looseleaf binder, a pair of opposed U strips, a set of binder posts carried by the base of each U, a pair of slidably superposed back elements, releasable means for latching said back elements in fully superposed relation and also in 25 partially extended relation, means hinging the U bases to the outer edges of the back elements, respectively, and means articulating each of the arms of one U to the corresponding arm of the other U to limit the pivotal movements of said 30 U strips.

7. In a looseleaf binder, a pair of opposed U strips, a set of binder posts carried by the base of each U, means permanently articulating each of the arms of one U to the corresponding arm 35 of the other U and permitting the arms of each articulated pair to be superposed, extended into alignment, or angularly adjusted out of alignment, a pair of slidably superposed back elements, means hinging the U bases to the outer edges of 40 the back elements, respectively, and releasable means for latching said back elements in fully superposed relation.

8. In a looseleaf binder, a pair of opposed U strips, a set of binder posts carried by the base of 45 each U, means permanently articulating each of the arms of one U to the corresponding arm of the other U and permitting the arms of each articulated pair to be superposed, extended into alignment, or angularly adjusted out of alignment, a 50 pair of slidably superposed back elements, means hinging the U bases to the outer edges of the back elements, respectively, and releasable means for latching said back elements in fully superposed relation and also in partially extended relation. 55

REGINALD M. RAYNOLDS.
